SIDE LOADING HEARSE MECHANISM

David E. Bench, Melvin A. Crosby, and George J. Wintermute, Dayton, Ohio, assignors to Commonwealth Engineering Corporation, Wilmington, Del., a corporation of Delaware

Application April 14, 1941, Serial No. 388,506

15 Claims. (Cl. 214—83)

This invention relates to a hearse of the side delivery type wherein a mechanism is provided for supporting a casket within the hearse and for rotating the support in a manner to alter its position from a longitudinal position within the hearse to a transverse position. In order to alter the position of a casket within a hearse from longitudinal to transverse with respect to the body, considerable space requirement is normally required as well as the provision of a rather wide opening through which the table supporting the casket can be moved.

It is an object of this invention to provide a mechanism which will alter the position of the casket supporting table with a minimum space requirement and with a minimum door opening.

It is another object of the invention to rotate the supporting table simultaneously with longitudinal movement thereof in a manner that the rotation bears a definite relation to the longitudinal movement.

It is another object of the invention to provide a mechanism for concomitantly rotating and longitudinally moving a casket supporting table so that for each increment of longitudinal travel the table will be imparted a definite increment of rotation.

It is another object of the invention to provide a gear mechanism for accomplishing the foregoing objects.

It is still another object of the invention to provide a gear mechanism for concomitantly rotating and longitudinally moving a casket supporting table wherein the gear mechanism for rotating the table bears a definite speed ratio to the gear mechanism for longitudinally moving the table so that the concomitant longitudinal movement and rotation alters the position of the supporting table to one transversely of the hearse and extends the same therefrom.

It is another object of the invention to provide a gear mechanism for rotating a casket supporting table within a hearse and a lead screw and cooperating nut mechanism for longitudinally moving the supporting table wherein the gear mechanism is driven by and synchronized with the lead screw mechanism for producing a predetermined path of travel of the supporting table.

It is another object of the invention to provide a common prime mover which is reversible in its driving motion for changing the direction of motion of the table.

It is another object of the invention to provide an electrical control mechanism for starting

the operation of the table support mechanism and for selecting the direction of rotation of the table to determine the side of the hearse through which it will extend.

5 Further objects and advantages will become apparent from the drawings and the following description.

In the drawings:

Figure 1 is a longitudinal cross-sectional view of the body of a hearse showing the normal position of the supporting table for the casket.

Figure 2 is a somewhat diagrammatic perspective view, partially in cross-section, of the drive mechanism for rotating the support table concomitant with longitudinal movement thereof and includes an electrical diagram of the control for the support.

Figure 3 is a cross-sectional view taken substantially along line 3—3 of Figure 4 showing the lead screw nut and the driving gears carried thereby in elevation.

Figure 4 is a cross-sectional view taken along line 4—4 of Figure 3.

Figure 5 is a cross-sectional view taken along line 5—5 of Figure 3.

Figure 6 is a perspective cross-sectional view taken along line 6—6 of Figure 5 showing the clutching mechanism between the worm wheel and the pinion of the drive gears.

30 Figure 7 is a somewhat diagrammatic perspective elevational view of a modified form of drive mechanism for the support table.

Figure 8 is a cross-sectional view taken along line 8—8 of Figure 7.

Figure 9 is a perspective elevational view of the transmission for changing the direction of rotation of the turret rotating mechanism in the reverse position from that disclosed in Figure 7.

Figure 10 is a cross-sectional view of a portion 40 of the body of a hearse showing the mechanism actuated by the doors thereof for shifting the transmission.

The hearse upon which this invention is to be used is of the type commonly known as the side delivery type. In a hearse of this general type the casket is normally carried within the body of the hearse in a longitudinal position, and when the casket is to be placed into the hearse or removed therefrom, the supporting table for the casket is moved into a position which is transverse with respect to the hearse body in a manner that a portion of the table extends from the side of the hearse. To permit the hearse body to be constructed as small as possible it is essential that the sweep of the path through

which the casket supporting table passes when changing from longitudinal to transverse position shall be restricted as much as possible. It is also convenient to reduce the opening in the side of the hearse through which the casket support table extends in order to permit more rigid body construction.

The hearse of the side delivery type usually consists of a body 10 having a rear opening door 11 and two side opening doors 12 and 13 which are pivoted to the body at 14 and 15 respectively. Two side entrance doors 16 and 17 pivotally carried by the body at 18 and 19 are provided for the driver of the vehicle to enter and leave the driver's seat 20. To gain as much longitudinal length as possible within the body of the hearse the driver's seat 20 is constructed and arranged to be moved into the dotted line position shown in Figure 1.

Within the body of the hearse 10 there is provided a casket supporting table 21 which is suitably carried upon the floor 23 of the hearse by means of a plurality of rollers 22 suitably secured to the under side of the supporting table 21. The rollers 22 are free to pivot upon a vertical axis so that the table 21 is permitted relatively free movement upon the floor 23 of the hearse.

A pivot post 24 is secured to the under side of the support table 21 by means of a flange member 25 which is integral with a cylindrical body portion 26. The body portion 26 extends downwardly through a longitudinal slot 27 provided in the floor 23 of the hearse and carries a circular flange 28 upon the end thereof. An internal gear 29 is carried upon the flange 28 in any suitable manner and is arranged coaxial with the body 26. The pivot post 24 is provided with a gear mechanism associated therewith for rotating the post about its axis through the internal gear 29 and is also provided with a lead screw nut which is engaged by a lead screw for moving the post 24 longitudinally within the slot 27. The lead screw and the gear mechanism are driven in synchronism so that longitudinal movement of the post 24 will be accompanied with concomitant rotation whereby the turret table 21 will be moved longitudinally within the hearse accompanied by concomitant rotation. This arrangement provides means for extending the forward end of the turret table 21 through the side wall of the hearse for access to the table.

The lead screw nut and the gear mechanism for actuating the post 24 comprise an assembly supported from the lower side of the floor 23 of the hearse. This assembly consists of a bracket member 30 having a flanged portion 31 secured to the floor 23 by means of the bolts 32. The bracket 30 also consists of a horizontally disposed wall 33 which is spaced from the floor 23 of the hearse and is adapted to form the lower half of a lead screw nut. The upper half of the lead screw nut consists of a wall member 34 which is suitably secured to the wall 33. A central bore 35 extends between the walls 33 and 34 and is suitably threaded to receive a lead screw 36. One end of the lead screw 36 is carried by a bearing bracket 37 positioned toward the forward end of the hearse and is prevented from shifting longitudinally of the hearse by means of the collars 38 which are suitably secured to the lead screw 36. The opposite end of the lead screw 36 is journaled within a bearing 39 provided in the bracket 30, the end of the lead screw extending through the bearing 39 and being supported by a ball bearing 40. The ball bearing 40 is carried within a recess

41 provided in the bracket 30 which is closed by a plate 42. The end of the lead screw carried in the ball bearing 40 is provided with a collar 43 which acts as a thrust member against the ball bearing 40 when the lead screw is rotated for moving the casket platform longitudinally within the hearse. A similar thrust bearing is preferably provided in the bearing bracket 37 to take up thrust in a direction opposite to the bearing 40.

A worm wheel 44 is carried upon the forward end of the lead screw 36 and is engaged by a worm 45 driven by an electric motor 46. The electric motor 46 is of the reversible type so that the lead screw 36 may be driven in either direction of rotation through the interconnecting worm and worm wheel. Suitable electrical mechanism hereinafter described is provided for reversing the current flow through the electric motor 46.

The upper wall 34 of the lead screw nut designated as 50 is provided with a vertical post 47 which is secured to the wall 34 in any suitable manner. A central bore 51 is provided within the body 26 of the pivot post 24 through which the post 47 extends. Recesses 52 and 53 are provided in the upper and lower portions respectively of the body 26 in which there are positioned the ball bearings 49 and 48 respectively. The post 47 is suitably journaled within the ball bearings 48 and 49 and carries a collar 54 upon the upper end thereof which rests upon the ball bearing 49. This bearing 49 thus provides a thrust bearing for the post 47 and the mechanism carried thereby.

The mechanism thus far described provides means for moving the pivot post 24 longitudinally within the slot 27 whenever the lead screw 36 is rotated in one direction or the other depending upon the position of the table 21 within the hearse.

To provide a mechanism for rotating the pivot post 24 concomitant with longitudinal movement thereof a worm 55 is journaled upon the lead screw 36 and is positioned within an internal opening 56 provided within the lead screw nut 50, which opening 56 is coaxial with the lead screw 36. Worm wheels 57 and 58 are journaled upon stub shafts 59 and 60 respectively, which shafts are carried by the lower wall 33 of the lead screw nut 50. A clutch mechanism to be herein-after described is interpositioned between each of the worm wheels 57 and 58 and its axle stud 59 or 60. The worm wheels 57 and 58 are both in engagement with the worm 56 carried upon the lead screw 36 so that upon rotation of the lead screw 36 the worm 56 will drive the worm wheels 57 and 58 in opposite directions of rotation.

To permit the worm 56 to move longitudinally upon the lead screw 36 while being driven thereby a key-way is provided therein within which a suitable key 62 carried by the worm 56 is adapted to slide upon longitudinal movement of the lead screw nut 50 with respect the lead screw 36.

The worm wheel 57 supports a pinion 63 which is also journaled upon the stub shaft 59 by means of the enlarged head 59a. The worm wheel 58 supports a pinion 64 which is also journaled upon the stub shaft 60 by means of an enlarged head 60a. The pinions 63 and 64 are freely rotatable upon their respective axle shafts 59 and 60 until engaged by a clutch mechanism herein-after described. The pinions 63 and 64 are in constant engagement with the internal gear 29 carried by the pivot post 24 so that either of the pinions can drive the pivot post 24 for rotation thereof depending upon the engagement of its cooperating clutch mechanism.

The clutch mechanism between the worm wheels 57 and 58 and the pinions 63 and 64, shown to a better advantage in the enlarged cross-sectional view of Figure 6, and since both of the mechanisms are identical only one is shown and described. The wall 33 of the lead screw nut 50 is provided with an internal bore 65 within which there is positioned a sleeve 66 carrying a pin 67 which extends radially toward the center of the sleeve 66. A second sleeve 68 is positioned within the sleeve 66 and is journaled upon the axle or stub shaft 59. An arcuate slot 73 is provided in the sleeve 68 into which the pin 67 extends. A second slot 71 is provided in the sleeve 68 and is vertically positioned therein to receive a pin 72 which extends from the stub shaft 59. The sleeve 66 is provided with teeth 73 in the outer periphery thereof and is engaged by a rack 74 for rotating the sleeve 66 with respect to the sleeve 68.

A sleeve 75 is journaled upon the stub or axle shaft 59 and is provided with a plurality of splines 76. The sleeve 75 is supported upon the sleeve 66 by means of the splines 76 so that when the sleeve 66 is rotated by means of the rack 74 the cooperation of the pin 67 with the slot 70 moves the sleeve 66 upwardly carrying the sleeve 75. The worm wheel 57 is provided with a splined internal bore 78 adapted to be engaged by the splines 76 of the sleeve 75 when the sleeve 75 is moved upwardly by means of the sleeve 66.

The normal position of the clutch mechanism for de-clutching the worm wheel 57 from the pinion 63 is as shown in Figure 6 so that the worm wheel 57 can rotate freely without causing rotation of the pinion 63.

As heretofore mentioned each of the worm wheels 57 and 58 are provided with the clutching mechanism which is described, the clutching mechanism 57a of the worm wheel 57 being actuated by the rack 74 while the clutching mechanism 58a for the worm wheel 58 is actuated by the rack 74a. The racks 74 and 74a are interconnected by means of a yoke 79 so that actuation of one of the racks actuates both whereby de-clutching of one of the clutch mechanisms causes clutching of the opposite mechanism.

The racks 74 and 74a are actuated by means of bellcrank levers 80 and 80a respectively which are pivotally carried upon the pivot supports 81 and 81a. The pivot supports 81 and 81a are secured to the under side of the floor 23 in any suitable manner as by the bolts 82 and 82a. The lever 80 is provided with an actuating arm or rod 83 which is connected to or actuated by the side door 12 of the hearse. The lever 80a is provided with an actuating arm or rod 83a which is connected to or actuated by the opposite hearse door 13. When the doors 12 and 13 are both closed the bellcrank levers 80 and 80a will be retracted from the racks 74 and 74a in the manner represented by the position of the lever 80 with respect to the rack 74. In Figure 5 the lever 80 is in the retracted position since the actuating rod 83 has been moved by the door 12 which is now closed while the lever 80a has been actuated by the door 13 to pivot the same about its pivot support 81a to actuate the rack 74. Figure 5 thus shows the position of the actuating arms 80 and 80a, one of which is in position with the door closed and the other is in position with the door open.

To retain the racks 74 and 74a in position upon actuation thereof spring pressed balls 84

and 84a engage detents 85 and 85a in the racks 74 and 74a respectively.

The electrical system for controlling actuation of the heretofore described apparatus consists of the electric motor 46 driving the worm 45 for rotating the worm wheel 44 which in turn actuates the screw 36. Rotation of the screw 36 causes the mechanism to function in a manner which will be hereinafter described.

10 The electrical controls consist of limit switches 86 and 87 one of which is positioned adjacent each end of the slot 27 in the floor 23 of the hearse and is adapted to be engaged by the pivot post 24 when the same approaches the ends of 15 the slot 27 whereby energization of the electric circuit to the electric motor 46 is controlled. The limit switch 86 deenergizes the electric motor 46 when the pivot post 24 has moved to its rearward position, which position is indicated in 20 Figure 1. The limit switch 87 deenergizes the electric motor 46 when the pivot post 24 is moved in its forward position representing the full extended position of the table 21 transversely of the hearse body 10. A double acting solenoid consisting of the armatures 88 and 89 energized by the coils 90 and 91 respectively is provided for actuating a relay 92 consisting of the blades 93, 94, 95 and 96.

25 A pair of push button switches is positioned adjacent each door 12 and 13, the push button switches 97 being connected in parallel and controlling the outward movement of the table 21, while the push button switches 98 are connected in parallel and control the inward movement of the table 21. The electric motor 46 is of the reversible type and is shown in the electrical diagram of Figure 2. The direction of flow of current to the armature is always in the same direction while the flow of current to the field is reversed in order to obtain forward and reverse rotation of the screw 36 for moving the table 21 in or out of the hearse body 10. The electric circuit for the motor 46 is energized from the battery 99 of the hearse. The limit switches 86 and 87 are normally closed unless engaged by the pivot post 24 so that the circuit shown in Figure 2 has the switch 86 in the open position representing the retracted position of the table 21 as shown in Figure 1. The push button switches 97 and 98 are of the momentary contacting type in order to energize the coil 90 or 91 for closing the relay 92 which is provided with a holding circuit represented by the contact blade 93. The relay 92, as shown in Figure 2, is in the normal deenergized position and is retained in this position by means of the compression springs 100 which oppose each other to balance the position of the armatures 88 and 89 within their respective actuating coils 90 and 91.

60 As will be seen from the former description the lead screw 36 and the worm 55 are driven by a common prime mover, the electric motor 46 and thus the driving ratio between longitudinal movement of the pivot post 24 and rotational movement thereof can be pre-determined to provide a definite increment of rotation of the pivot post 24 for each increment of forward travel thereof. The pivot post 24 moves parallel with the axis of the hearse body 10 with concomitant rotation so that the table 21 is moved forwardly with simultaneous rotation whereby the position of the table is changed from parallel with the axis of the body to transverse of the axis and in a position forward of its position when within the hearse. This movement also

extends the table 21 from one side or the other of the hearse body in accordance with the predetermined direction of rotation for the rotating mechanism of the pivot post 24.

In order to extend the table 21 from the hearse the door 17 may be opened in the conventional manner and the driver's seat 20 be shifted forwardly into the dotted line position shown in Figure 1. If the table is to be extended through the left side of the hearse as shown in Figure 1 the door 13 will be opened whereby the control rod 83a tends to actuate the rack 14a. Movement of the rack 14a rotates the sleeve 66 of the cooperating clutching mechanism 58a in order to raise the splined sleeve 75 whereby the worm wheel 58 is placed in driving engagement with the pinion 64. The push button 97 positioned adjacent the door 13 is actuated to engage its cooperating contacts to close circuit to the coil 90 for actuating the armature 88 and thereby pull the relay 92 in an upwardly direction to close circuit through the upper set of contacts for each of the blades 93, 94, 95 and 96. The blade 93 provides a holding circuit for the coil 90 so that when the push button 97 is released the coil 90 will not become deenergized. The blades 94, 95 and 96 control the direction of flow of current to the armature and the field of the electric motor 46 so that the screw 36 is rotated in the proper direction for advancing the table forward and outwardly of the hearse 10.

Since the clutch 58a drivingly connects the worm wheel 58 with the pinion 64 rotation of the lead screw 36 also rotates the worm 55 for rotating the worm wheel 58. The pinion 64 being in constant engagement with the internal gear 69 secured to the pivot post 24 will rotate the pivot post simultaneously with the forward advancement of the post by means of the lead screw 36. Since the driving ratio has been established between the lead screw 36 and the gearing mechanism for rotating the pivot post 24, the post 24 will be rotated a predetermined angular increment for each increment of forward motion thereof whereby the table 21 is moved forwardly and concomitantly rotated to advance and extend the same from the hearse body 10. When the pivot post 24 approaches the forward end of the slot 27 it will engage the limit switch 87 to open the circuit to the coil 90 whereby the relay 92 is deenergized and the mechanism thus halted in its operation.

When the table 21 is to be returned to within the body of the hearse the push button switch 98 is actuated to close circuit through its cooperating contacts whereby circuit will be made through the coil 91 since the limit switch 86 is now in the closed position. The armature 89 will be moved in a downwardly direction to close the blades 93, 94, 95 and 96 upon the cooperating lower sets of contacts. The blade 93 provides a holding circuit for the coil 91 while the blades 94, 95 and 96 energize the electric motor 46. When the relay blades are in the lower position the direction of flow to the armature to the electric motor 46 is retained in the same direction as when the blades are in their upper position. However, the direction of flow of current to the field of the motor 46 is reversed to the direction of flow from when the blades are in their upper position.

The lead screw 36 will thus be driven in an opposite direction of rotation from that previously described whereby the pivot post 24 will be

moved in a rearward direction and concomitantly rotated to retract the table 21 with the same motion provided for its forward advancement.

In Figures 7 to 10 inclusive there is shown a modified form of apparatus for producing the same type of motion as produced by the apparatus heretofore described. The essential elements of the mechanisms are identical in that a lead screw is used to produce longitudinal motion of the pivot post while a worm and worm wheel arrangement is provided for producing rotative motion of the pivot post. The lead screw and the worm are driven from a common prime mover, the worm obtaining its power from the lead screw and the two elements are driven in a predetermined speed ratio which produces predetermined rotative increment of the pivot post for each increment of longitudinal movement thereof.

In this arrangement the pivot post 110 carries a worm wheel 111 which is rotated by means of a worm 112 carried upon a feed rod 113. The feed rod 113 has a key slot 114 adapted to engage a suitable key in the worm 12 to permit the same longitudinal movement along the feed rod 113 while being rotated thereby.

The pivot post 110 has a depending portion 115 which extends below the worm wheel 111 and carries an enlarged head 116. The head 116 is adapted to be positioned within a recess 117 provided in the lead screw nut 118. A cover plate 119 engages the upper surface of the head 116 and retains the same in cooperating engagement with the lead screw nut 118.

The feed rod 113 which carries the worm 112 is bearinged in a bracket 120 carried upon the lead screw nut 118. A lead screw 125 is in threaded engagement with the lead screw nut 118 through a suitable threaded bore 121 provided longitudinally in the lead screw nut 118. The lead screw 125 carries a worm wheel 122 suitably secured thereto which is drivingly engaged by a worm 123, which worm 123 is secured upon the shaft of an electric motor 124.

The electric motor 124 is of the reversible type to drive the lead screw 125 in either direction of rotation according to the movement desired for the casket supporting table 21.

In order to rotate the pivot post 110 while longitudinally moving the same within the slot 27 in the floor 23 of the hearse a gear train is provided between the lead screw 125 and the feed rod 113. The gear train thus provides means for transmitting power from the electric motor 124 to the feed rod 113 so that a common prime mover is used for driving the lead screw 125 and the feed rod 113. The gear train is also adapted to function as means for reversing the direction of rotation of the feed rod 113 with respect to the lead screw 125 so that the pivot post 110 can be rotated in either direction of rotation for extending the table 21 through the desired side of the hearse 10.

The gear train consists of the spur gears 126 and 127 carried upon the lead screw 125 and suitably secured thereto. A pair of spur gears 128 and 129 is carried upon a sleeve 130 which sleeve is journaled upon the feed rod 113 and is provided with a suitable key in engagement with the key slot 114 to permit the sleeve to move longitudinally upon the feed rod 113 while at the same time driving the same rotatively through means of the key and key slot. An idler gear 131 is interpositioned between the gears 127 and 129 in order to reverse the direction of rotation of the

feed rod 113 when being driven thereby from the direction of rotation caused by the driving engagement of the gears 126 and 128.

When the casket supporting table is to be extended from the hearse 10 the electric motor 124 is energized whereby the lead screw 125 is rotated to cause the lead screw nut 118 to advance toward the forward end of the hearse and thereby carry the pivot post 110 toward the forward end of the hearse. Concomitant with this motion the feed rod 113 rotatably drives the worm 112 to cause rotation of the pivot post 110, the power for such drive being obtained either through the gears 126 and 128 or the gears 127, 131 and 129. If the gears 126 and 128 are in meshing relationship as shown in Figure 7 the direction of rotation of the pivot post 110 will be such as to rotate the forward end of the table 21 to extend the same through a selected side of the hearse whereas if the gear 129 is brought into meshing relationship with the gear 131 the direction of rotation of the pivot post 110 will be in the opposite direction. This opposite direction of rotation of the pivot post 110 can thus be accomplished even though the worm wheel 122 rotates in the same direction if the pivot post 110 is to be advanced toward the forward end of the hearse.

In order to return the casket table 21 to within the hearse the direction of rotation of the motor 124 is reversed in a manner heretofore referred to by the description of the electrical diagram shown in Figure 2.

A mechanism is provided for automatically selecting the direction of rotation of the pivot post 110 in accordance with which of the doors 12 or 13 is opened, thereby determining the side of the hearse through which the table 21 will extend. This mechanism consists of a shifting fork 132 which engages an under-cut portion 133 provided in the sleeve 130. The fork 132 is pivotally mounted at 134 and has an extending arm 135 carrying a pin 136.

A pair of rods 137 and 138 extend transversely of the hearse 10 and are suitably carried in the bearing supports 139 and 140 respectively. Collars 141 and 142 are provided on the rods 137 and 138 respectively and have compression springs 143 and 144 respectively positioned between the collars 141 and 142 and their cooperating bearing posts 139 and 140 respectively.

The rod 137 engages the door 12 while the rod 138 engages the door 13 so that upon opening of either of the doors the corresponding rod will be moved outwardly by its actuating spring. The inner ends of the rods 137 and 138 are provided with slots 145 and 146 respectively through which the pin 136 extends. The device, as shown in Figure 10, has been actuated by the door 13 to shift the gears 128 and 129 to one of their positions. If the door 13 is again opened there will be no actuation of the pinion 136 or the fork 132 since the slot 146 will permit movement of the rod 138 without engaging the pin 136. This result is obtained since the mechanism is arranged that once it has been shifted it will not move until the mechanism has been shifted in the opposite direction by the opening of the other door. Thus the arrangement of the device of Figure 10 is such that if the door 12 is opened the rod 137 will be actuated by the spring 143 whereby the slot 145 engaging the pin 136 will cause the arm 135 to rotate the fork 132 and thus shift the sleeve 130.

Since the worm 112 is geared directly to the screw 125 the speed of operation thereof can be

predetermined to obtain rotation of the pivot post 110 in predetermined increments for each increment of longitudinal travel thereof with respect to the hearse body whereby a predetermined path of travel for the casket table 21 is created.

Having thus fully described our invention what we claim as new and desire to secure by Letters Patent is :

1. In a side loading hearse, means for supporting a casket, a pivot post for said support, a lead screw nut and a gear means carried by said post, gear means in engagement with said gear means carried by said post for rotating said post, a lead screw in engagement with said nut for moving said post longitudinally of said hearse, gear means in engagement with said lead screw, clutch means disposed between said first mentioned gear means and said last mentioned gear means, means for actuating said clutch means to interconnect said aforementioned gear means, and power means for rotating said lead screw to move said casket support longitudinally of the hearse and simultaneously rotate said pivot post at a predetermined speed ratio to position said casket support transversely of the hearse.

2. In a side loading hearse, means for supporting a casket, a pivot post for said support, a lead screw nut and a gear means carried by said post, gear means in engagement with said gear means carried by said post for rotating said post, a lead screw in engagement with said nut for moving said post longitudinally of said hearse, gear means in engagement with said lead screw, clutch means disposed between said first mentioned gear means and said last mentioned gear means, means for actuating said clutch means to interconnect said aforementioned gear means, and power means for rotating said lead screw to move said casket support longitudinally of the hearse and simultaneously rotate said pivot post at a predetermined speed ratio to rotate said support a determined angular increment for each increment of longitudinal travel thereof for placing said casket support transversely of the hearse at a predetermined longitudinal position thereof.

3. In a side loading hearse, means for supporting a casket, a pivot post for said support, longitudinally extending screw means operatively associated with said post for longitudinally moving the same, and gear means operatively associated with said screw means and said post for rotating said post in a determined ratio to the longitudinal movement thereof for placing said casket support transversely of the hearse at a predetermined longitudinal position thereof.

4. In a hearse, a table, means providing a pivotal axis for said table, a lead screw engaging said means for moving the same longitudinally of the hearse, gear means engaging said means for rotating the same, power means for driving said lead screw, and means interposed between said lead screw and said gear means for selecting the direction of rotation of said pivotal means.

5. In a hearse, a table, means providing a pivotal axis for said table, a lead screw engaging said pivotal means for moving the same longitudinally of the hearse, gear means engaging said pivotal means for rotating the same, gear means in engagement with said screw and rotated in opposite directions, power means for driving said lead screw, and clutch means interposed between said oppositely rotating gear means and said gear means in engagement with said pivotal means for selecting the direction of rotation of said pivotal means.

6. In a hearse, a table, means providing a pivotal axis for said table, a lead screw engaging said means for moving the same longitudinally of the hearse, gear means engaging said means for rotating the same, a common power means for driving said lead screw and said gear means at speeds having a predetermined ratio, whereby said gear means rotates said axis a determined angular increment for each increment of longitudinal travel thereof, and means actuated by the opening of one of the doors of the hearse for selecting the direction of rotation of said axis.

7. In a hearse, a table, means providing a pivotal axis for said table, a lead screw engaging said means for moving the same longitudinally of the hearse, gear means engaging said means for rotating the same, a common power means for driving said lead screw and said gear means at speeds having a predetermined ratio, whereby said gear means rotates said axis a determined angular increment for each increment of longitudinal travel thereof, means actuated by the opening of one of the doors of the hearse for selecting the direction of rotation of said axis, and means for reversing the motion of the power means for reversing the motion of said axis.

8. In a hearse of the side delivery type, a table, a pivot post for said table, a gear means and a lead screw nut carried by said post, a lead screw engaging said nut, power means for driving said lead screw, a pair of oppositely rotatable gear means for transmitting power from said lead screw to said gear means on said post for rotating said post concomitant with longitudinal movement thereof by means of said lead screw, and gear means disposed between said oppositely rotatable gear means and said gear means on said post for selecting the direction of rotation of said post.

9. In a hearse of the side delivery type, a table, a pivot post for said table, a gear means and a lead screw nut carried by said post, a lead screw engaging said nut, power means for driving said lead screw, and gear means for transmitting power from said lead screw to said gear means on said nut for rotating said post concomitant with longitudinal movement thereof by means of said lead screw, said gear means providing the means for selecting the direction of rotation of said post, said power means being reversible to reversely drive said lead screw.

10. In a hearse, a table having means providing a pivotal axis, a lead screw engaging said means for moving the table longitudinally of the hearse, a pair of gear means driven by said lead screw for oppositely rotating said axis means, and means for shifting the driving connection from said lead screw to one or the other of said gear means for determining the direction of rotation of said axis.

11. In a side delivery hearse, a table having a pivot post, a lead screw nut and gear means carried by said post, a lead screw in operative engagement with said nut, power means for said screw, gear means disposed adjacent opposite sides of said screw and in engagement therewith

for opposite rotation, pinion gear means disposed upon each of said last mentioned gear means and in engagement with said gear means on said post, and clutch means disposed between said pinion gear means and the gear means supporting same for controlling the driving engagement of said pinion gear means with said lead screw.

12. In a side delivery hearse, a table having a pivot post, a lead screw nut and gear means carried by said post, a lead screw in operative engagement with said nut, gear means carried by said nut for drivingly engaging said first mentioned gear means, said last mentioned gear means being driven by said lead screw, clutch means for controlling the driving engagement of said last mentioned gear means with said lead screw, and means actuated by the doors of the hearse for operating said clutch means.

13. In a hearse of the side delivery type a table having a pivot post, a lead screw nut and a gear means carried by said post, a lead screw in driving engagement with said nut, power means for rotating said lead screw, gear means disposed adjacent opposite sides of said screw and in engagement therewith for opposite rotation, pinion gear means carried by each of said last mentioned gear means which drivingly engages said gear carried by said post, and clutch means disposed between said pinion gear means and the gear means supporting same for drivingly connecting said pinion gear means with the gear means supporting same, and means for selectively actuating said clutch means to select the direction of rotation of said post.

14. In a hearse of the side delivery type means for supporting a casket having a pivot post, a lead screw nut and gear means carried by said post, a lead screw in engagement with said nut, gear means in driving engagement with said gear carried by said post, a feed rod drivingly engaging said last mentioned gear means, and gear means drivingly interconnecting said lead screw and said feed rod for driving the same concomitantly, said last mentioned gear means providing a shiftable transmission for drivingly rotating said feed rod in either direction of rotation with respect said lead screw.

15. In a hearse of the side delivery type means for supporting a casket having a pivot post, a lead screw nut and gear means carried by said post, a lead screw in engagement with said nut, gear means in driving engagement with said gear carried by said post, a feed rod drivingly engaging said last mentioned gear means, gear means drivingly interconnecting said lead screw and said feed rod for driving the same concomitantly, said last mentioned gear means providing a shiftable transmission for drivingly rotating said feed rod in either direction of rotation with respect said lead screw, and means actuated by opening of a door of the hearse for shifting said transmission.
